UNITED STATES PATENT OFFICE.

PATRICK DORAN, OF BROOKLYN, ASSIGNOR TO HENRY C. MEYER & CO.,
OF NEW YORK, N. Y.

FAUCET.

SPECIFICATION forming part of Letters Patent No. 228,736, dated June 15, 1880.

Application filed April 9, 1880. (No model.)

To all whom it may concern:

Be it known that I, PATRICK DORAN, of Brooklyn, in the county of Kings and State of New York, have invented a certain new and useful Improvement in Faucets; and I do hereby declare that the following is a full and exact description thereof, reference being had to the accompanying drawings, making part of this specification.

10 Prior to my invention, in that kind of faucet in which was employed a valve that closed with the pressure, and which was moved toward and from its seat by means of an eccentric-pin on the inner end of the spindle, (which kind of faucet is best known in the market as the "Fuller" faucet,) there was more or less liability of the valve, under certain conditions, to rattle or make more or less noise in seating or in approaching its seat, and this liability 15 was an objection to the use of this kind of valvular faucet.

My invention has for its object to overcome this objection in this kind of faucet; and it consists in the combination, with the valve, 25 of a spring or yielding device or devices adapted to hold the valve laterally, while at the same time permitting it to assume the various positions necessary to its movement by the crank-motion of the eccentric-pin on the inner end of the spindle, all as will be hereinafter set forth.

To enable those skilled in the art to make and use my improved faucet, I will now proceed to more fully describe it, referring by 30 letters to the accompanying drawings, in which—

Figure 1 is a side sectional view of an ordinary cock, such as known for many years in the market as the "Fuller" faucet, but having my invention embodied therein. Fig. 2 is a 40 partial horizontal section of the same; and Fig. 3 is a detail perspective view of the valve, with its attachments, separate from the other portions of the faucet, for the purpose of more fully illustrating my invention.

In the several figures the same part will be found designated by the same letter of reference.

A is the main body portion of the faucet, 50 and B is the nozzle or outlet-pipe, while C is

the spindle, D the stuffing-box surrounding the same, and E the handle, all made and arranged in about the manner usual in a Fuller faucet, familiar to those skilled in the art.

h is the elastic bulb-like valve, having a sort 55 of conical rear portion, and provided with the usual stem g, the free end of which is hung on and pivoted to the inner end of the spindle C, through the medium of the eccentric-stud or wrist-pin f, in the manner and for the purposes well known, said valve having its seat at o.

i are the usual lateral projections on the stem g, radiating from the stem in a plane which, if extended, would pass substantially 65 through the axis of the wrist-pin f, and which projections serve to hold the valve-stem properly in place relatively to the said wrist-pin f; and m are the yielding or elastic projections or spring-like arms extending outward from 70 the said stem g, on opposite sides thereof, and in a plane at right angles to the plane of the lugs i, in such manner that their ends bear against the walls of the water-way in which the valve-stem moves, or against the bore of 75 the passage in which said valve lies, as plainly illustrated.

With the exception of such variations as are effected by the elastic arms or yielding guides m, the operation of the faucet and the 80 movements of its parts are about the same as usual in the kind of faucet shown; but by reason of the combination with the valve-stem g of the yielding guides m, acting in conjunction with walls or fixed portions of the water-way, 85 as shown and described, the valve and its stem, while they are permitted to assume the positions and make the movements necessary in the opening and closing of the valve by the action of the wrist-pin f, (which, of course, 90 moves in a circle or arc,) are prevented from vibrating or oscillating or performing any movements which might cause any rattle of any part of the valve or stem against any other part of the contrivance, and are effectually prevented from performing any fluttering movement, when the valve is either partially or wholly open, that might cause any jar or noise in the faucet or pipes connected therewith, during either the continuous flow or the 95 100

stoppage of the flow of liquid through the valve-chamber or water-way of the faucet.

It will be understood, of course, that in lieu of the form shown of spring-holders *m*, yielding or elastic steadyng devices of other form, and otherwise applied to the valve or its stem, may be employed without departing from the spirit of my invention, the gist of which rests in the combination, with the valve, of some suitable means or devices adapted to permit the necessary vibrations or wave-like motions of the valve, (that result from its movement toward and from its seat by the impelling eccentric pin or stud *f*.) and at the same time prevent any casual lateral movement or any fluttering of the valve from any other cause during its opening or closing, or while standing open.

Without, therefore, limiting myself to any precise form or particular location of the elastic holder devices or steadyng devices,

What I claim as new, and desire to secure by Letters Patent, is—

The combination, with the valve of that kind of faucet in which the valve closes with the pressure and has its stem pivoted to a crank-pin or eccentric, of a yielding or elastic device or means for restricting the lateral movements of the valve, substantially as and for the purposes set forth.

In witness whereof I have hereunto set my hand.

PATRICK DORAN.

In presence of—

SAM. F. SNIFFEN,
W. C. MEYER.
